UNITED STATES PATENT OFFICE.

JOSÉ MIGUEL TORRES Y CURBELO, OF HABANA, CUBA.

REFRIGERATOR.

Application filed February 2, 1927, Serial No. 165,437, and in Cuba January 17, 1927.

This invention refers to refrigerators, and has for its main object, the substitution of the coil, which is used in devices of this kind, for a chamber wherein the water is forced 5 to circulate exactly in an analogous relation to the circulation in a coil, but with the very important advantage, that said chamber is provided with a dismountable cover or bottom which permits of inspection and cleaning 10 of same.

Up to the present time, it has been observed that the greatest inconvenience in coils has been, that, the lack of adequate facilities for cleaning, causes the accumulation of 15 filth, containing microbes or pathogenic bacteria in the pipe, which causes the development of different diseases.

With this invention, the cleaning of the circulation chamber, may be effected by any- 20 one with little experience, and at will; said chamber may be galvanized or enamelled in- nerly and outerly.

Another advantage of this invention, is that the refrigerating surface is considerably 25 increased, with respect to the refrigerating surface of the coil in use, which is never in complete contact with the ice and besides, has dead spaces, that is to say, those spaces caused by the bend in the pipe, and causing a 30 considerable waste of ice, the refrigerating power of which is not absorbed by the coil.

Another advantage of the invention is that the chamber of circulation, has a capacity for a greater volume of water than that 35 which may be contained in a tubular coil.

The invention is shown in the attached drawings and described in the course of these specifications, wherein the same characters of reference designate the same parts in the 40 different views.

Fig. 1, is a side elevation in detail of the improvement, object of the present invention.

Fig. 2, is an upper plan view of same.

Fig. 3, is a plan view of the lower part of 45 said improvement.

Fig. 4, is a longitudinal vertical section according to lines 4—4 of Fig. 2.

Fig. 5, is a vertical transversal section ac- 50 cording to lines 5—5 in Fig. 2.

Fig. 6, is a horizontal section according to lines 6—6 of Fig. 1.

Fig. 7, represents a section equivalent to that shown according to lines 5—5 of Fig. 52, in a modified form of the invention.

Fig. 8, shows a section equivalent to that

shown, according to lines 4—4 of Fig. 2 in said modification.

Fig. 9, is a horizontal section of said modification equivalent to the horizontal section 60 shown, according to lines 6—6 in Fig. 1.

Referring to the Figures 1 to 6 inclusive, in same is designated by 1, a metallic case of rectangular form, and placed in an inverted position, that is, with its bottom 1' up, and 65 its open part down. Said case has its interior divided in a plurality of passages 2, separated incompletely the one from the other by partitions 3 which are cut off on their ends in alternate relation, to each other, as 70 clearly shown in Fig. 6, so that all are inter-communicated.

Said case 1 is supported and closed by a rectangular plate 4 by the intermediation of a sheet of material for hydraulic joint 5, being secured with respect to the plate 4 by set screws 6, screwed on ears 1" projecting from the ears of the case 1, passing through coinciding bores opened in ears 4" projecting from the plate or cover 4, and having screwed 80 on the projecting ends of said screws 6, the nuts 6'.

This case 1 has on one of its sides recesses 1'" in which is opened threaded bores 7 and 8, the liquid inlet pipe 9 being screwed in 85 the bore 7 and the outlet pipe 10 in the bore 8.

The plate 4 is supported by legs 11, with insulator caps 12.

Upon the upper part 1' of the case 1 are 90 placed the blocks of ice 13, of course the whole of the arrangement shown being inclosed in a refrigerator cabinet which is not shown.

In this way, the liquid passing through the 95 pipe 9 circulates continuously and zigzag- gedly through the passages 2 which are formed between the partitions 3, in the di- rection indicated by the arrows in Fig. 6, exactly in the same way as the water cir- 100 culates in the usual coils and finally being drawn when desired through the pipe 10.

If case 1 is to be repaired or cleaned, the nuts 6' are unscrewed and the box 1 is raised, leaving the interior of same exposed, making 105 it possible to clean same thoroughly.

It will be noted that as the block of ice 13 rests upon the upper part 1' of the refrigeration and circulation chamber, the area of contact is greater than that existing in the 110 coils now in use, and therefore the refrigeration is more complete; to this may be added

the capacity of the chamber 1 in which a considerable reserve of cold water may be kept.

In the Figures 7, 8 and 9 is shown a modified form of the invention, showing the case

5 1 comprising a current passage 14 formed by two partitions in circumvolutions 15 and 16 directed in opposite directions the one from the other, and ending in the center of the case, and which passage extends from 10 the inlet pipe 17 to the outlet or drawing opening 18 as may be clearly seen in Fig. 9.

The liquid therefore circulates in the direction indicated by the arrows in said Fig. 9 in the same manner as in the coils in use.

15 Instead of two partitions, there may be only one in form of circumvolutions forming the passage of circulation for the liquid.

It is obvious that within the principles of construction before explained, many modi-

fications may be made, within the main 20 idea of the invention, which is as claimed hereunder.

Claim:

In refrigerating apparatus, a casing forming a chamber having a closed top and 25 sides and an open bottom, said casing being formed internally with baffles extending from the top to the plane of the bottom, arranged to conduct cooling liquid in a tortuous path through said casing, and a 30 removable bottom for said casing having a plane upper surface engaging the edges of the sides of said casing and the edges of said baffles in water tight relation.

In testimony whereof I have signed my 35 name to this specification.

JOSE MIGUEL TORRES Y CURBELO.
